UNITED STATES PATENT OFFICE.

GEORGE A. GLENN, OF LAWNDALE, PENNSYLVANIA.

MEANS FOR MAKING BRICKS.

Application filed December 30, 1921. Serial No. 525,879.

To all whom it may concern:

Be it known that I, GEORGE A. GLENN, a citizen of the United States, residing at Lawndale, in the county of Philadelphia and 5 State of Pennsylvania, have invented new and useful Improvements in Means for Making Bricks, of which the following is a specification.

This invention relates to means for making bricks and it has more particular reference to manually operated brick making machines, that is to say, machines of the type which are manipulated by hand.

The primary object of this invention is to 15 provide a hand operated device for making bricks or blocks which is characterized by the fact that as the outer sides or walls of the mold—as well as any division web or webs—are simultaneously drawn upwards 20 away from the aggregate the pressure or force caused by the weight of said mold is thrust directly and evenly over the upper surface of the green aggregate.

Another object of my invention is to provide 25 an improved hand operated device for making bricks having a series of divisions each of which contains a number of cores, whereby bricks are produced which can be broken with facility at any desired position for filling odd spaces or completing 30 lines of masonry work.

A further object of this invention is the provision of a brick making device by the use 35 which apertured bricks are produced which readily lend themselves to interlocking connection when bonded together either by the use of ordinary mortar or by grouting, reinforced or otherwise.

A still further object attained by this invention 40 is the provision of a brick making device capable of turning out bricks of different density or porosity, and incidentally due to their apertured formation of relatively less weight.

Another object attained by my invention 45 is consequent upon providing the mold with a bridging frame having supporting legs which—when the flask portion is raised to liberate the molded aggregate or bricks—50 serve to prevent said aggregate or bricks from being crushed out of shape by the downward thrust exerted when lifting said flask and the friction of its walls thereagainst.

Still further objects resulting from my invention are economy in material and produc-

tion costs whilst labor expense in building with bricks produced by my improved means is correspondingly reduced.

With the foregoing and other objects in view as will be more apparent from the following disclosure, this invention consists essentially in certain novel features of construction, combinations and arrangements of parts hereinafter fully described, and more specifically defined by the appended claims.

In the further disclosure of the invention reference is to be had to the accompanying sheets of explanatory drawings illustrating one practical embodiment thereof, and in which drawings corresponding or like parts are designed by the same reference characters.

Figure 1—is a top plan view of my improved brick or block forming device.

Figure 2—is a side elevation of the same with part broken away or in section for the sake of clearness, and the raised or brick discharging position being indicated by dotted lines.

Figure 3—is a bottom plan view of the device with the operating handles removed; and,

Figure 4—is a transverse section taken substantially on the line 4—4 in the preceding Figure.

Referring more particularly to the views which as before stated are illustrative of one practical embodiment of my invention only, I construct a rectangular frame or flask 5 of suitable material which is divided by transverse walls or integral partitions 6 to provide a series of molds 7 of the requisite dimensions to produce the desired size of bricks or blocks. For ease in description the longer or side walls of the frame or flask 5 are designated by the numeral 8 and the shorter or end walls by the numeral 9. Upset relative to and integral with the side walls 8 I provide a series of spaced brackets 10, the upper ends whereof are bossed to provide journals for rods or shafts 11 on which are loosely pivoted the operating handles 12, later on more specifically described.

Disposed outside each end wall 9 of the frame or flask 5 are standards or legs 13 which are overhung or inwardly deflected at their upper parts 14 so that they repose over said end-walls 9, and integral with the upper ends thereof are downwardly curved arms 15 having flanged ends 16 for connection to the false bottom plates 17 by countersink screws

18 for example. The upper parts 14 of the standards or legs 13 are rigidly connected together in proper spaced relation by means of a cross-piece or member 19 and countersink screws 20, said cross-piece or member 19 being inset therein as shown to prevent any lateral displacement or warp of the standards or legs 13 relative to the frame or flask 5.

10 Securely attached by countersink screws 21 to the underside of the aforesaid cross-piece or member 19 are spaced inner and outer cam-path frame members 22, 23 respectively, which are likewise connected securely to the aforesaid false bottom plates 17 by screws 24 and thus it will be readily seen and clearly comprehended by those conversant with the art that the standards or legs 13, cross-piece or member 19, and cam-path frame members 22, 23 are all rigidly connected together, with the frame or flask 5 free to be moved relative thereto as hereafter explained. It is to be here particularly observed that the inner cam-path frame members have a cut away or removed part indicated most clearly in Figure 4 by the numeral 25 whereby a slight reduction in weight results.

Disposed longitudinally of the aforesaid frame or flask 5 and seating on the inner edges thereof is what I term a multiple core-grid 26 having a plurality of integrally formed core pieces 27 of appropriate cross section to produce correspondingly shaped holes or apertures through the bricks or blocks produced by my novel molding device. This multiple core-grid 26 is conveniently clamped to the outer face of the frame or flask end walls 9, 9 by means of 30 screw 28 passed through ears 29 on said grid threading into correspondingly screwed holes provided for their reception, and it will also be noted that the core-pieces 27 are slightly tapered to ensure an easy draft 35 when the frame or flask is withdrawn from off the finished aggregate.

Referring back again to the operating handles 12 it will be observed that each said handle is of what may be conveniently 40 termed inverted knee-shaped pattern in side view and that they each comprise a hand-grip portion 30 integral with spaced limbs 31; each of said limbs terminating in parallel curved forked members 32 through 45 which are passed the aforesaid rods or shafts 11. The free ends of these forked members 32 are slotted at 33—Figure 2—to provide bearings for anti-friction rollers 34 adapted to traverse the hereinbefore described cam-path frame members 22, 23; and the axles 50 35 for said rollers 34 are securely riveted or otherwise attached to side plates 36 removably connected to the forked members 32 by screws 37. Thus it will be readily seen 60 that by removing the screws 37 the side

plates 36, attached axles 35 and anti-friction rollers 34 can be easily taken out and replaced whenever desired, whilst a simple means is provided for the ready assembly and dismantling of the just described parts. 70

Holes 38 are provided in the false bottom plates 17 for the free passage therethrough of the cores 27 when the frame or flask 5 is raised or withdrawn from off the finished 75 bricks or blocks.

In use and assuming as shown that my improved brick or block forming device is for the making of three said bricks or blocks at one and the same time the position of said device will be as shown by Figure 3. In 80 this position it will be obvious that the material or aggregate can be filled into the three molds 7 according to prevailing practice. The device is then inverted or turned bottom side up as shown by Figures 1 and 85 4 and in this position it will be supported by the foot pieces 39 of the standard or legs 13. The operator now takes hold of the hand grips 30 and draws them upwardly and inwardly with an arcuate movement towards 90 each other as shown by the dotted lines in Figure 2, said movement causing the anti-friction rollers 34 to travel downwards in the cam-path frame members 23. This 95 downward movement of the anti-friction rollers 34 due to the pivotal connection of their supporting forked members 32 rocking on the rods or shaft 11 will result in the uniform and bodily raising as a unit of the frame or flask 5 with its integrally connected 100 partitions 6 and attached cores 27, whilst the false bottoms 17 will remain seated on the upper surface of the molded bricks or blocks. The entire device can now be drawn off upwardly from the finished bricks or 105 blocks or otherwise removed clear of the same without any frictional disruption or disturbance to said bricks or blocks.

From the foregoing it will be seen that by my invention I have evolved a very practical and efficient means for molding or forming bricks or blocks of any desired shape and configuration and I wish it here understood that my device may be used as a rigid or stationary mold, in which case the flask 115 walls, core grid, and false bottom plates will be upwardly drawn simultaneously free of the molded material. When the device is used in this manner the surfaces of the inner false bottoms will be faced with sponge 120 rubber felt-fiber or other soft cushion materials finished off with a layer of sheet rubber, leather, oil-skin canvas or such non-porous materials as desired that will act as a cushioning means to prevent the suction of aggregate to mould bottom when loaded and thereby preventing breaking or fracturing to the edges and corners of the moulded bricks or blocks so that the same 125 will be discharged from the mould as a 130

whole. This method of discharging the aggregate is effected by the shock of the rigid legs 13 striking the unloading bed with force, the impact forces aggregate as mould 5 is lifted, due to fiber and rubber cushion which breaks the suction bond.

Whilst there has been shown and described one practical embodiment of my invention the same is not to be construed in any restricted sense, as it will be obvious the same 10 is susceptible of many structural changes without departing from its essential features or method of operation; for example, the flask may be mechanically raised, inverted or transported, and the right is therefore hereby reserved to make such variations and other combinations as fairly lie within the scope of the appended claims.

Having described my invention, what I 20 claim as new and desire to secure by Letters Patent is:

1. A mold for making bricks or blocks comprising a rectangular frame having transverse partitions and projecting brackets 25 about one of its peripheral edges, a false bottom for each mold constituted by said transverse partitions, said false bottoms being disposed in a common plane and supported in the rectangular frame by a cross-bearer and opposed standards outside the same, spaced cam paths intermediate said standards connecting the false bottoms and cross bearer, a multiple core grid secured centrally longitudinal of the rectangular frame and having a 30 plurality of core members projecting through correspondingly shaped apertures in the false bottoms for producing apertured bricks or blocks, and manually operable rockable members connecting the rectangular frame brackets with the cam paths whereby said rectangular frame may be moved relative to the false bottoms to release the molded bricks or blocks whilst exerting a downward thrust evenly 35 thereover.

45 2. A mold for making bricks or blocks comprising a rectangular frame having transverse partitions and projecting brackets about one of its peripheral edges, a false bottom for each mold constituted by said transverse partitions, said false bottoms being disposed in a common plane and supported in the rectangular frame by a cross-bearer, and opposed standards outside the same, spaced cam paths intermediate said standards connecting the false bottoms and cross bearer, a multiple core grid secured centrally longitudinal of the rectangular frame and having a 50 plurality of core members projecting through correspondingly shaped apertures in the false bottoms for producing apertured bricks or blocks, and movable means connecting the rectangular frame brackets with the cam paths whereby said frame, multiple core-grid and false bottoms 55 may be upwardly moved clear of the molded bricks or blocks.

60 3. A mold for making bricks or blocks including a rectangular frame having transverse partitions, opposed projecting brackets about one of its peripheral edges, and a multiple core grid secured longitudinally central thereof, said core grid having a 65 plurality of core members for producing

frame may be moved relative to the false bottoms to release the molded bricks or blocks whilst exerting a downward thrust evenly thereover.

3. A mold for making bricks or blocks 70 comprising a rectangular frame having transverse partitions and projecting brackets about one of its peripheral edges, a false bottom for each mold constituted by said transverse partitions, said false bottoms being disposed in a common plane and supported in the rectangular frame by a cross-bearer and opposed standards outside the same, spaced cam paths intermediate said standards connecting the false bottoms and cross-bearer, 75 a multiple core grid secured centrally longitudinal of the rectangular frame and having a plurality of core members projecting through correspondingly shaped apertures in the false bottoms for producing apertured 80 bricks or blocks, opposed vertically rockable forked members pivotally mounted between the aforesaid projecting brackets, and laterally journaled antifriction rollers mounted on the inner ends of the forked members, said 85 antifriction rollers co-operating in the aforesaid cam paths whereby said rectangular frame may be moved relative to the false bottoms to release the molded bricks or blocks 90 whilst exerting a downward thrust evenly 95 thereover.

4. A mold for making brick or blocks comprising a rectangular frame having transverse partitions and projecting brackets about one of its peripheral edges, a false bottom for each mold constituted by said transverse partitions, said false bottoms being in a common plane and covered with resilient material and having a non-porous facing thereover, a cross bearer and opposed standards outside the rectangular frame for supporting the false bottoms, spaced cam paths intermediate the opposed standards outside the rectangular frame for supporting the false bottoms, spaced cam paths intermediate the opposed standards connecting the false bottoms and cross bearer, a multiple core grid secured centrally longitudinal of the rectangular frame and having a plurality of core members projecting through correspondingly shaped apertures in the false bottoms for producing apertured bricks or blocks, and movable means connecting the rectangular frame brackets with the cam paths whereby said frame, multiple core-grid and false bottoms 100 may be upwardly moved clear of the molded bricks or blocks.

5. In a mold for making bricks or blocks 105 including a rectangular frame having transverse partitions, opposed projecting brackets about one of its peripheral edges, and a multiple core grid secured longitudinally central thereof, said core grid having a plurality of core members for producing 110

apertured bricks or blocks, the combination of a false bottom for each separate mold in the rectangular frame, said false bottoms being disposed in a common plane and supported from a cross bearer and opposed standards outside the rectangular frame, cam paths intermediate the opposed standards connecting the false bottoms to the cross bearer, and rockable forked members

fulcrumed between the aforesaid projecting brackets in operative engagement with the cam paths whereby said rectangular frame and multiple core grid may be moved relative to the false bottoms to release the molded bricks or blocks.

In testimony whereof I affix my signature.

GEORGE A. GLENN.
